2 SHEETS-SHEET 2.

UNITED STATES PATENT OFFICE

ROBERT MIEHLE, OF CHICAGO, ILLINOIS.

FEED-TABLE FOR PRINTING-PRESSES.

1,111,718.

Specification of Letters Patent. Patented Sept. 22, 1914.

Application filed February 24, 1914. Serial No. 820,474.

To all whom it may concern:

Be it known that I, ROBERT MIEHLE, a citizen of the United States, residing at Chicago, in the county of Cook and State 5 of Illinois, have invented certain new and useful Improvements in Feed-Tables for Printing-Presses, of which the following is a specification.

The invention has for its object an improvement in the feeding mechanism of printing presses whereby to obtain uniformity of action under changing conditions.

Ordinarily the feed table is of wood equipped with a metal terminal lip which 15 extends tangentially into close relation to the cylinder onto which the sheet is delivered. As, however, the wood is subject to swelling, warping and contracting under varying atmospheric conditions and the lip 20 is supported directly thereon, the relation of the latter to the cylinder also changes, and the uniformity of the feeding action is affected detrimentally.

By the present invention I employ preferably as a part of the feed table a metallic supporting frame by which the wooden feed board is carried, the frame having a metallic terminal lip which forms in effect a continuation of the board and extends to a 30 position closely adjacent and substantially tangent to the cylinder. As the lip is carried by the frame and is independent of the board it is not affected by any warping or swelling of the latter and maintains at all 35 times a constant relation between the feed table and cylinder whatever the atmospheric influences upon the board. The side gages are also usually carried by the board and are thus affected by any changes in the latter. 40 such as those referred to. By mounting these gages independent of the board on the frame or lip uniformity in the positioning of the sheet is secured.

A further feature of the invention is the 45 provision of improved registering means whereby to secure an accurate positioning of the lip relative to the cylinder as the feed table swings from an elevated inoperative position to an operative position. To this 50 end I employ a coacting stud or socket provided with adjusting means to regulate the extent to which the former may enter the latter.

In the accompanying drawings and in the 55 description based thereon is set forth a pre-

ferred embodiment of the invention. As, however, the same is susceptible of embodiment in other and varied constructional forms and modifications the drawing and description are to be taken in an illustrative 60 and not in an unnecessarily limiting sense.

In the drawings: Figure 1 is a top plan view of the feed board and adjacent parts with certain portions broken away; Fig. 2 is a side elevation of Fig. 1; and Fig. 3 is a 65 fragmentary view on an enlarged scale of the forward portion of the feed board showing the registering device.

In the drawings the printing cylinder is represented at 11 with the front gages 12 supported thereabove upon the rock shaft 13. The feed table is tiltably mounted on the shaft 14 suitably carried by the frame work 15 and comprises a metallic frame 16 counterweighted at 17 and having a terminal lip 18 suitably secured thereto at 19. A further 70 element of the feed table is the feed board 20 carried by the frame 16 and having its upper face in the same plane as the metallic lip 18 which latter forms in effect an independent continuation of the board. Adjustably mounted upon the terminal lip 18 by means of the screw 21 is a side gage 22 by which the sheets are laterally positioned to enter upon the cylinder. Mounted upon the 75 lower side of the lip 18 and projecting forwardly thereof is shown a thin metallic apron 23, which, under some circumstances, 80 may be dispensed with, the apron forming in effect the tip of the lip 18. 90

For properly registering the feed table in its operative position a device is provided which consists of a noncircular stud 24 which may be oval or polygonal in cross section, this stud being carried by a bracket 25, 95 fixed to the frame 16 and consequently moving with the feed table. Coöperating with the stud 24 and formed within an integral portion 26 of the cylinder frame is a socket corresponding in cross sectional shape and 100 size to the stud and adapted to snugly receive the latter so that the stud entering the socket will accurately position the feed table laterally and longitudinally. Threaded within the member 26 adjacent the socket is a set screw 27 having a shoulder 28 which underlies the socket and is adapted to be engaged by the lower end of the stud whereby the extent to which the stud may enter the socket is accurately controlled by the 110

regulation of the set screw 27 and the vertical positioning of the feed table with reference to the cylinder is secured. It will thus be seen that that portion of the feed table which coats directly with the cylinder is entirely independent of the feed board 20 and that any changes in the latter due to atmospheric or other conditions have no effect whatever upon the relation of the feed table as a whole to the cylinder, or to the adjustment of the side gages; also that the proper registering of the feed table in its operative position is effected between coöperative parts carried respectively by the metallic frame of the feed table and of the cylinder so that such registering is secured and maintained independent of any variations in the feed board.

I claim:

20 1. In a printing press, the combination with a cylinder, of a hinged metal frame, and a feed board carried thereby, such frame having a metal terminal lip forming an independent continuation of the board, substantially as described.

2. In a printing press, the combination with a cylinder, of a hinged metal frame, and a feed board carried thereby, such frame having a metal terminal lip forming an independent continuation of the board, and gages carried by the frame and independent of the board, substantially as described.

3. In a printing press, the combination with a cylinder, of a movable frame, a feed board carried thereby, said frame having a metal terminal lip forming an independent continuation of the board, said frame mounted to swing the lip from an inoperative position to an operative position adjacent to the cylinder, and a registering device arranged to accurately position the lip with reference to the cylinder in its operative position, substantially as described.

4. In a printing press, the combination with the cylinder, of a tiltable frame, a feed board carried thereby, said frame having a metal terminal lip forming an independent continuation of the board, said frame mounted to swing the lip from the elevated position above the cylinder to a position closely adjacent and substantially tangent thereto, and a registering device arranged to accurately position the lip with reference to the cylinder in its lowered position, substantially as described.

5. In a printing press, the combination with a cylinder, of a tiltable frame, a feed board carried thereby, a registering device arranged to accurately position the board with reference to the cylinder in its operative position, said registering device comprising a stud and coöperating socket, one carried by the frame and the other by a suitable support, and means to vary the ex-

tent to which the stud may enter the socket, substantially as described.

6. In a printing press, the combination with the cylinder, of a tiltable frame, a feed board carried thereby, said frame having a metal terminal lip forming an independent continuation of the board, said frame mounted to swing the lip from the elevated position above the cylinder to a position closely adjacent and substantially tangent thereto, and a registering device arranged to accurately position the lip with reference to the cylinder in its lowered position, said registering device comprising a non-circular stud and coöperating socket, one carried by the frame and the other by a suitable support, and means to vary the extent to which the stud may enter the socket, substantially as described.

7. In a printing press, the combination with the cylinder, of a tiltable frame, a feed board carried thereby, said frame having a metal terminal lip forming an independent continuation of the board, said frame mounted to swing the lip from an elevated position above the cylinder to a position closely adjacent and substantially tangent thereto, and a registering device arranged to accurately position the lip with reference to the cylinder in its lowered position, said registering device comprising a non-circular stud carried by the frame, a correspondingly shaped socket fixed upon a suitable support and adapted to receive the stud, a set screw adjustable in the support, and means controlled by the set screw to vary the extent to which the stud may enter the socket, substantially as described.

8. In a printing press, the combination with a cylinder, of a tiltable frame, a feed board carried thereby, said frame mounted to swing the board from an inoperative position to a position adjacent and substantially tangent to the cylinder, and a registering device arranged to accurately position the board with reference to the cylinder in its operative position, said registering device comprising a noncircular stud carried by the frame, a correspondingly shaped socket fixed upon a suitable support, and adapted to receive the stud, a set screw adjustable in the support and having a portion underlying the socket and arranged to be engaged by the stud to vary the extent to which the latter may enter the socket, substantially as described.

9. In a printing press, the combination with the cylinder, of a tiltable frame, a feed board carried thereby, said frame having a metal terminal lip forming an independent continuation of the board, said frame mounted to swing the lip from an elevated position above the cylinder to a position closely adjacent and substantially tangent thereto, and a registering device arranged

to accurately position the lip with reference to the cylinder in its lowered position, said registering device comprising a non-circular stud carried by the frame, a correspondingly shaped socket fixed upon a suitable support and adapted to receive the stud, a set screw adjustable in the support and having a shoulder underlying the socket and arranged to be engaged by the stud to vary

the extent to which the latter may enter to the socket, substantially as described.

In testimony whereof I have hereunto signed my name in the presence of two subscribing witnesses.

ROBERT MIEHLE.
